Primary Examiner — Cynthia Ramirez(74) *Attorney, Agent, or Firm* — Adler Pollock & Sheehan P.C.; George N. Chaclas, Esq.; Daniel J. Holmander, Esq.(57) **CLAIM**

The ornamental design for a valve body, as shown and described.

DESCRIPTION

FIG. 1 is a front view of the valve body according to the present disclosure.

FIG. 2 is a back view of the valve body according to the present disclosure.

FIG. 3 is a right side view of the valve body according to the present disclosure.

FIG. 4 is a left side view of the valve body according to the present disclosure,

FIG. 5 is a top view of the valve body according to the present disclosure; and,

FIG. 6 is a bottom view of the valve body according to the present disclosure.

The broken lines shown in the figures are included for the purpose of illustrating portions of the valve body and form no part of the claimed design.
